GONIOMETER

Randhir S. Dhir, 850 Amsterdam Ave., Apt. 17D,
New York, N.Y. 10025

Filed Sept. 4, 1969, Ser. No. 19,028

Term of patent 14 years

Int. Cl. D24—02

U.S. Cl. D52—6

FIG. 1.

FIG. 2.

FIG. 3.

FIG. 4.

FIG. 1 is a top plan view of a goniometer showing my new design;

FIG. 2 is a right side elevational view;

FIG. 3 is a bottom plan view;

FIG. 4 is an elevational view from the bottom of FIG. 1;

FIG. 5 is a top plan view of a goniometer showing another form of my new design;

FIG. 6 is a bottom plan view; and

FIG. 7 is a right side elevational view.

I claim:

The ornamental design for a goniometer, substantially as shown and described.
